UNITED STATES PATENT OFFICE.

EDWARD L. ORCUTT, OF SOMERVILLE, MASSACHUSETTS; FRED A. MADDOX, OF MEDFORD, MASSACHUSETTS, AND ELMER N. HUTCHINS, OF SOMERVILLE, MASSACHUSETTS, EXECUTORS OF SAID ORCUTT, DECEASED.

APPARATUS FOR ELECTRICALLY CONTROLLING AIR-BRAKES.

1,114,643.

Specification of Letters Patent. Patented Oct. 20, 1914.

Application filed March 15, 1913. Serial No. 754,440.

To all whom it may concern:

Be it known that I, EDWARD L. ORCUTT, a citizen of the United States, and a resident of Somerville, in the county of Middlesex 5 and State of Massachusetts, have invented a new and useful Improvement in Apparatus for Electrically Controlling Air-Brakes, of which the following is a specification.

The object of the present invention is to 10 provide means whereby the engineer may be prevented from releasing the air brakes until the train or other vehicle provided with said brakes has been brought to a full stop, or else the speed thereof reduced to a predetermined rate.

The drawing which accompanies and forms a part of this specification illustrates one form of apparatus and circuit arrangements whereby my invention may be carried 20 into effect; but it will be understood that both the apparatus and circuit arrangements may be subjected to a wide range of variation without departing from the principle of my invention.

In the drawing the figure represents dia- 25 grammatically one embodiment of my im- proved locking device shown in connection with an apparatus for electrically controlling air brakes, which I have described and 30 claimed in my application Serial No. 507,278, filed July 12, 1909.

The casing 10 of the blanking valve 17 is to be attached to the train-line pipe (not shown) by the nuts 9. The casing is pro- 35 vided with a chamber 12 having a bushing 13 and carrying a movable abutment shown in the present instance as a piston 14 at- 40 tached to the rod 16 which is guided by the cap 20. The movement of the piston rod is communicated to the blanking valve 17, which slides upon the seat 18, by the shoul- 45 ders 22, and the spring 19 holds said valve upon its seat. The retaining valves 26, 27, which are suitably constructed to control the pressure in the train-line pipe, are connected to the pipe 24 which communi- 50 cates with the chamber 23 when the valve is in its blanking position and the valve 28 is located to cut out the retaining valve 26.

The pipe 34, connected between the main reservoir (not shown) and the passages 31 in the casing 10, valve seat 35 and cap 38, conveys the compressed air from the main

reservoir to the chamber 39 in said cap. 55 The rotary valve 43 is provided with ports, one of which is shown at 52. The port 52 communicates with the chamber 56 upon the face of the valve, which in the running position of the valve, overlies the ports 49 and 50 in the valve seat. The valve seat 35 60 is provided with the port 51 with which, by means of the valve-port 55, the chamber 39 of the cap communicates when the valve is in cut-off position, thereby permitting the main reservoir pressure to pass to the chamber 12. The valve-operating handle 40 is attached to the valve by the stem 42 and nut 41, said stem terminating as shown in a tenon which co-operates with a key-way formed in the upper part of the valve. The 65 valve is centered by the pin 46 in the recess 45 of the valve seat.

The casing 57 of the electrically-operated valve 58 is attached to the casing 10 through the insulating bushing 156. The electrically-operated valve 58 normally closes communication between the passage 49 and the whistle 66 and is secured to the piston rod 59, to which the armature 64 of the electro- 75 magnet 60 is attached. The electromagnet 60 is energized by the battery 68 and the circuit of said magnet and battery contains a suitable circuit controller such as the key 70.

When the circuit of the battery 68 and 85 magnet 60 is opened, the armature 64 falls to the bottom of the casing 63, its travel being limited by the adjustable stop 62, thereby uncovering the seat of the valve 58, so that the pressure above the piston 14 is relieved by way of the port 50, chamber 56, 90 passage 49 and whistle 66 and the pressure from the train-line pipe causes said piston to rise. The movement of the piston brings the port 18 into communication with the 95 pipe 24 through the chamber 23 thereby allowing the train-line pipe to discharge and set the brakes, and the whistle 66 will continue to blow until the valve 58 is closed.

The brakes may be released by throwing 100 the handle 40 to cut-off position, whereupon, as above stated, the full pressure of the main reservoir will pass to the chamber 12 by way of the pipe 34, passages 31, chamber 39, and ports 55 and 51, thereby driving the 105 piston 14 and blanking valve 17 down to re-

leasing position, so that the engineer's brake-valve (not shown) can recharge the train-line pipe to its full releasing pressure.

The brake-releasing mechanism above described can be operated independently of the speed of the train or other vehicle carrying the same, and in order to prevent the engineer from releasing the brakes by throwing the handle 40 to cut-off position until the train has been stopped or its speed reduced to a safe rate, I provide a speed-controlled device for locking the handle 40, such device preferably being electrically actuated, and in addition I may employ means for maintaining said device in its locking position.

As shown in the particular embodiment of my invention selected for illustrating the principle thereof, the handle-locking device consists of a pin 90 arranged to pass through the hole 93 in the cap 38 and the hole 91 in the bracket 92 integral with the said handle. The pin is carried by the armature 89 of the magnet 86 and is held in retracted position out of the hole 93 by the spring 94 when said magnet is deenergized. By the closure of the circuit of the battery 84 connected with said magnet by wires 85, 87, as for example by bringing the circuit-controller 82 against the contact 88, the magnet will be energized, and the resulting attraction of its armature 89 will drive the pin through the hole 93 and thereby lock the handle in running position, so that the brakes cannot be released until the circuit of the battery is opened.

The speed-controlled device for actuating the circuit-controller 82 may consist of any suitable centrifugally-operated mechanism, such as the governor, 81, attached to the sleeve 81' which supports but is not secured to the lever 82. The governor may be connected to any rotating part of the train, such as the shaft 80, which is shown for purposes of illustration as connected by the beveled gears 76, 79 with the axle 78.

It will now be obvious that when the key 70 is opened, either automatically or manually as the case may be, the brakes will be set, and if the train is traveling at so low a speed that the circuit of magnet 86 is open, the handle 40 may be thrown to cut-off position and the brakes released; but if the speed be such that the governor 81 forces the sleeve 81' against the lever 82 and throws the latter against the contact 88, thereby closing the circuit of the magnet 86, the handle will be locked in running position and render the release of the brakes impossible until a safe speed has been reached. I may also employ the latching device 103 for holding the circuit-controller 82 in circuit-closing position, in which case the handle will remain locked until the lever 82 is un-

latched. In the present instance, the magnet 100, which is in circuit with the battery 101 and two contacts closable by the spring 102 carried by the sleeve 81', automatically unlatches the lever 82 when the speed is reduced to a predetermined rate or the train brought to a full stop, the relative position of the contacts and spring being adjustable, so that the magnet 100 will not be energized until the train has been stopped or such predetermined speed reached.

I claim:

1. The combination in an air-brake system, of means for setting the brakes, means for releasing the brakes, a speed-controlled device for locking said brake-releasing means in non-releasing position and means for maintaining said device in locking position.

2. The combination in an air-brake system, of means for setting the brakes, means for releasing the brakes, a speed-controlled device for locking said brake-releasing means in non-releasing position, means for maintaining said device in locking position, and means for releasing said device from its locking position.

3. The combination in an air-brake system, of means for setting the brakes, means for releasing the brakes, a speed-controlled device for locking said brake-releasing means in non-releasing position, means for maintaining said device in locking position, and speed-controlled means for releasing said device from its locking position.

4. The combination in an air-brake system, of means for setting the brakes, means for releasing the brakes, a device for locking the brake-releasing means in non-releasing position, an electromagnet for controlling said device, a speed-controlled switch for the circuit of said electromagnet, means for holding said switch in circuit-closing position, and speed-controlled means for releasing said switch.

5. The combination in an air-brake system of a rotary valve, a locking device arranged to lock said valve in brake-setting position, and speed-controlled means for controlling said device.

6. The combination in an air-brake system of a casing, a rotary valve arranged in said casing, a handle secured to said valve, a pin co-operating with said valve and casing, means for actuating said pin, and a speed-controlled device for controlling said means.

In testimony whereof, I have hereunto subscribed my name this 13th day of March 1913.

EDWARD L. ORCUTT.
